United States Patent Office

Des. 188,852
Patented Sept. 20, 1960

188,852

FIGURINE

Arthur T. Bruggisser, 561 NE. 79th St., Miami, Fla.

Filed Oct. 26, 1959, Ser. No. 58,063

Term of patent 14 years

(Cl. D29—23)

FIG. 3

FIG. 2

I claim:

The ornamental design for a Figurine, substantially as shown.
